WILLIAM P. PATTON, OF HARRISBURG, PENNSYLVANIA, ASSIGNOR TO HIMSELF, THEOPHILUS WEAVER, AND ISAAC LLOYD, OF SAME PLACE.

Letters Patent No. 70,109, dated October 22, 1867.

IMPROVEMENT IN SWITCHES.

The Schedule referred to in these Letters Patent and making part of the same.

TO ALL WHOM IT MAY CONCERN:

Be it known that I, WILLIAM P. PATTON, of Harrisburg, county of Dauphin, and State of Pennsylvania, have invented a new and useful Improvement on a Switch-Stand and Lock; and I do hereby declare the following to be a full, clear, and exact description thereof, reference being had to the annexed drawings, making a part of this specification, in which—

Figure 1 represents a perspective view of the switch-stand.

Figure 2, a section through the key, lock, guard, arch, &c.

Figure 3, showing lock, locking-bolt, and spring.

Figure 4, showing the disk.

Figure 5, showing the disk and the key.

Figure 6, showing key-hole plate and part of the lever.

Figure 7, showing partly the outside of lock, guard, and lever, partly a section through lock, guard, &c.

Figure 8, showing the bolt-holes in arch.

The nature of my invention consists in constructing, combining, and arranging the several parts of this switch-stand and lock so that the key can only be taken from the lock when the switch is in connection with the main track, and there securely locked.

The switch-stand A, fig. 1, is made substantially the same in form as the ordinary upright lever switch-stand, with this exception, that the arch B upon our improved stand has its sides parallel, and is without the projections that are formed upon the ordinary stand for the detention of the lever V. Upon the said arch B, at its ends b', two shoulders are made, upon which the ends of the guard C rest, and are firmly fastened. Said guard C has its edges curved, forming arcs of two concentric circles, whose centre is at the point c'. This guard is made of such width that the lower edge or arc of the minor circle shall nearly touch the barrel of the key, when said key is inserted in the lock, as shown in fig. 1. The purpose of the guard C is to hold the lever in its proper position against the arch. Between the guard and the arch a space intervenes for the reception of the lever. Said lever has its fulcrum at d', and is intended to communicate motion to the track in the ordinary manner, and is connected with it by a ground rod at the lower end. Upon this lever, at a point just below the arch, the body of the lock E is rigidly attached in such manner as to be immovable until the lever itself is removed from the stand. The lock-body is of such size, in relation to the operating mechanism in it, as will insure a proper degree of strength. In said body a rectangular hole is formed nearly throughout its entire length. This hole or cavity has its upper end open for the reception of the locking-bolt F. This bolt is rectangular, and of such length as to permit its upper end to project a proper distance above the lock-body, when the lock is locked, while at the same time its lower end is in connection with the disk. This connection is effected by forming a groove or channel, G, in the body of the bolt, near its lower end, on the side next the disk H. This groove has its sides parallel with the lower end of the bolt, and is of sufficient depth and width to receive the connecting-pin formed on disk. This disk is inserted in a round hole or recess, that is formed in the lock-body at right angles to the cavity that contains the locking-bolt. Said round hole is made of such depth in relation to the bolt-cavity as to cut into it, thus exposing the groove in the locking-bolt F, when said bolt is in place. The intersection of these holes forms two abutments at the bottom of the round hole, upon which the disk rests and revolves. This disk is made circular in form, and of proper thickness, and has the connecting-pin before mentioned projecting from the side, that is, in contact with the locking-bolt, as shown in figs. 3 and 4. It also supports the key-post I upon its opposite side. This key-post is cylindrical in form, and is firmly inserted in the body of the disk H. It is provided with the sleeve K, so fitted as to revolve easily upon it. Said sleeve is retained in place by having one of its ends in contact with the disk, and the other against a shoulder, formed on the outer end of the key-post. This sleeve is designed to prevent the lock being unlocked with nippers or similar instruments. Disk H is also provided with an indentation or hole, L, for receiving a boss or projection, L', that is formed upon the ward of the key N. At a point, M, on disk H, a pin or shoulder projects. (See figs. 4 and 5.) On the key-hole plate a similar projection, O, is formed, against which the projection impinges when the lock is locked, thus preventing the key from being turned in the wrong direc-

tion. It will be noticed upon inspection of figs. 4 and 5 that the hole L, pin p' , and key-post have their centres in a right line when the lock is locked. It will also be observed that the projection O, on plate R, is a short distance out of said line of their centres. Under bolt F a spiral spring, P, is placed. It is made of proper strength, and bears against the lower end of the bolt, for the purpose of supporting it, and aiding the action of the key. The key-hole plate R is fastened securely to the body of the lock, and is so formed as to make a suitable facing for it. Said plate is provided with a circular boss, S, in which the key-hole is formed. Said boss fits neatly in and passes entirely through a hole which is formed in the lever for its reception. The key-hole is made to admit the key readily, and is flared or widened from the inner side outwardly, as shown in fig. 2 at R'. The key-hole plate also has a circular flange, Y, projecting from its inner surface, which nearly touches the disk and keeps it in place. The guard has a notch cut in its lower edge, at a point, T', directly opposite the hole in the arch B. This notch is of a proper size to admit the key, or to release it, when the lever is in a perpendicular position. The arch of the switch-stand A has three holes, b'' b' b', formed in its under side. These are formed for the reception of the locking-bolt. The holes b' b' are to lock the switch, when it is turned for a siding. The centre hole, b'', is intended to lock the same on the main track. The holes b' b' are made of less depth than the centre hole. Immediately below the key-hole (see fig. 1) a carved projection, U, is formed upon the lever V. This is of the same thickness as the guard C, and consequently its outside surface is in the same plane with the outside of guard C, and it extends around the key-hole until it nearly touches the lower edge of guard C. This projection answers two purposes: first, in connection with the key-hole cover X it forms a closed bar to protect the lock from exposure; second, it secures the key from icecles, that will form on the lower edge of guard C in winter. Said key-hole cover X is attached to guard C immediately above the notch in its lower edge. (See fig. 1.)

The several parts of this switch-stand and lock being placed in proper position as they are represented in fig. 1, are operated in the following manner:

The key being inserted in the lock until the ward touches the disk, the projection or boss L' upon said ward enters the depression made for its reception in disk H. The key is then turned to the right, until its ward strikes the projection M, figs. 4 and 5, which, from its position in relation to the key-post, permits the ward of the key to pass over the centre of said post, and thus retains it in position, when the lock is unlocked. The ward is of exact size to fill the lateral section of the cavity or space between the key-hole plate R and the disk H, thereby retaining the boss on said ward in the indentation made for it in the disk, and preventing the key from being released or withdrawn, after it has been turned beyond the key-hole. The disk is made to turn by the action of the key, and communicates its motion to the bolt, by means of the pin travelling in the groove in bolt E. The bolt being depressed in the manner above described, the lever can be moved and the track adjusted to either siding that may be desired. In moving the lever the key is carried away with it from the notch in the guard C, and consequently cannot be released or taken out, as its motion is contingent upon the ascent of the bolt, and said bolt is prevented from having its full throw, by the holes b' b' being of less depth than b'', but of sufficient depth to hold the lever, and consequently the switch, upon the sidings. In returning the lever to a vertical position, the switch is returned to the main track. The key can now be released or taken from the lock by locking the same, the centre hole being of sufficient depth to permit the full throw or ascent of the locking bolt F. When locked said bolt cannot be forced down by external pressure, as the pin p' in groove G is in a vertical line with the centre of disk, and consequently upon a dead-point.

What I claim as my invention, and desire to secure by Letters Patent, is—

I claim a lock so constructed as that the key can only be withdrawn when the bolt is completely thrown, when the same is used in combination with the operating mechanism of a railroad switch, and so arranged in relation to the bolt-holes as that the bolt can only be entirely thrown when the switch is in connection with the main track, substantially as set forth.

In testimony whereof I have signed my name to this specification in the presence of two subscribing witnesses.

WM. P. PATTON.
